Patented July 21, 1914.

UNITED STATES PATENT OFFICE.

RALPH M. HYDE, OF WESTFIELD, NEW YORK.

FURNACE-DAMPER REGULATOR.

1,104,509.

Specification of Letters Patent.

Patented July 21, 1914.

Application filed March 26, 1913. Serial No. 756,951.

To all whom it may concern:

Be it known that I, RALPH M. HYDE, a citizen of the United States, and a resident of Westfield, in the county of Chautauqua and State of New York, have made certain new and useful Improvements in Furnace-Damper Regulators, of which the following is a specification.

My invention relates to improvements in furnace damper regulators, and it consists in the combinations, constructions, and arrangements herein described and claimed.

An object of my invention is to provide means for automatically regulating the dampers on furnaces used in vapor or low pressure steam heating systems.

A further object is to provide means for regulating the dampers, said means comprising a device of the gasometer type with a novel device for preventing the forcing of the water in the gasometer out of the same by the steam pressure, and also for preventing the entrance of air into the gasometer when the steam pressure has lowered.

Other objects and advantages will appear in the following specification and the novel features of the device will be particularly pointed out in the appended claims.

My invention is illustrated in the accompanying drawings forming part of this application in which—

Figure 1 is a perspective view of the regulator, and Fig. 2 is a sectional view thereof.

In carrying out my invention I provide an exterior tank or casing 1 which is provided with a top 2 having a central opening 3. The top 2 is provided with a central boss 4. The upper side of the boss is surfaced as shown at 5, while the lower side of the boss 4 is also surfaced or ground off, as shown at 6.

On the interior of the stationary tank or casing 1 is a movable bell-shaped member 2. This is provided with a boss 7 which has a ground surface 8. The boss 7 is threaded to receive a rod 9 which is arranged to pass through the opening 3 and is provided with a threaded end 9^x arranged to receive a cap 10. The cap 10 is provided with a ground surface 11.

A steam pipe 12 leading from the boiler (not shown) connects with a T 13 to which is connected a pipe 14 that extends upwardly into the casing 1. The upper end of the pipe 14 is open. A pipe 15 is threaded into the T 13 and forms a standard for the gas-

ometer device, being provided with a base 16 as shown in Fig. 1.

The cap 10 has integrally extending arms 17 to which are attached links 18 connecting with a semicircular yoke 19. This yoke has an integral lever arm 20 pivoted at 21 on an arm 22 which is secured to the outer casing 1 by means of a band or split ring 23.

The lever arm 20 is provided with an adjustable weight 24. The end of the arm 20 is connected with the check damper 25 of the furnace 26 by means of a cord 27 which passes over a pulley 28. The damper 29 which controls the direct draft of the furnace 26 is connected to the arm 20 by means of a cord 30.

From the foregoing description of the various parts of the device the operation thereof may be readily understood.

The tank 1 is filled with water 31 up to the top of the pipe 14. Steam passing in through the pipe 12 enters the space 32 between the inner bell-shaped member 2 and the top of the water 31, and the pressure of the steam causes the bell to rise, thus forcing the arm 9 upwardly and causing the turning of the lever arm 20 on its pivot. The downward movement of the lever arm 20 will cause the opening of the check damper 25 and the closing of the direct draft damper 29. As the steam pressure goes down and the bell descends the lever arm 20 will be swung in the opposite direction and the direct draft damper 29 will be opened, while the check damper 25 will be closed, as shown in Fig. 2.

The main feature of my invention and the part which I consider novel is the means for preventing the forcing of the water out of the casing 1. It will be observed that when the bell 2 has risen to its upper limit the surfaces 8 and 6 will come in contact. These surfaces are ground true and they form a steam-tight joint. The pressure of the steam on the interior of the bell 2 holds these parts securely together and therefore there is no danger of the water 31 in the casing 1 being forced outwardly between the bell and the casing and thence out through the opening 3. This would certainly occur if the steam pressure was high enough unless this means is provided for preventing it.

On the other hand when the inner bell has descended to its lowest position due to the lowering of the steam pressure the ground surface 11 of the cap 10 will come in contact

with the ground surface 5 of the boss 4 and will prevent any further entrance of air into the device. The cap 10 therefore acts as an effectual air seal and thus insures the proper 5 working of the system which would be materially interfered with should the air be permitted to enter after the bell has reached its lowest point.

I claim:

- 10 1. In a draft regulator for steam boilers, an outer casing, a top therefor provided with a central boss having an opening therethrough, said boss extending above the outer surface of the top and below the inner surface 15 of the top, the upper and lower faces of the boss being surfaced or ground, a bell-shaped member disposed within said outer casing and being provided with a central boss at its top having an upper face ground to form a tight fit with the lower face of the first named boss, a rod carried by the boss on said bell-shaped member and arranged to extend through the opening in the first named boss, a cap carried at the upper end 20 of said rod having a lower surface ground to permit a tight fit with the lower face of the first named boss, a lever, flexible connections between said lever and the dampers of the furnace, and connections between 25 said cap and said lever for operating the lever through the movement of the cap.
2. In a draft regulator for steam boilers, an outer casing, a top therefor provided with a central boss having an opening therethrough, said boss extending above the outer surface of the top and below the inner surface 30 of the top, the upper and lower faces of the boss being ground, a bell-shaped member disposed within said outer casing and being provided with a central boss at its top having an upper face ground to form a tight fit with the lower face of the first named boss, a rod carried by the boss on said bell-shaped member and arranged to 35 extend through the opening in the first named boss, a cap carried at the upper end of said rod having a lower surface ground to permit a tight fit against the upper surface of said first named boss, a lever, flexible connections between said lever and the dampers of the furnace, and connections between 40 said cap and said lever for operating the lever through the movement of the cap.
- 45 3. In a draft regulator for steam boilers, an outer casing, a top therefor provided with a central boss having an opening therethrough, said boss extending above the outer surface of the top and below the inner surface of the top, the upper and lower faces of the boss being surfaced or ground, a bell-shaped member disposed within said outer casing and being provided with a central boss at its top having an upper ground face to form a tight fit with the upper face of the first named boss, a rod carried by the boss on said bell-shaped member and arranged to extend through the opening in the first named boss, said rod being smaller than the opening to provide clearance between the rod and the walls of the opening, and a cap carried at the upper end of said rod having a lower surface ground to permit a tight fit against the upper surface of 50 said first named boss.

RALPH M. HYDE.

SOLON C. KEMON.

links connecting the ends of said arms with said yoke.

3. In a draft regulator for steam boilers, an outer casing, a top therefor provided with a central boss having an opening therethrough, said boss extending above the outer surface of the top and below the inner surface of the top, the upper and lower faces of the boss being ground, a bell-shaped member disposed within said outer casing and being provided with a central boss at its top having an upper face ground to form a tight fit with the lower face of the first named boss, a rod carried by the boss on said bell-shaped member and arranged to extend through the opening in the first named boss, a cap carried at the upper end of said rod having a lower surface ground to permit a tight fit against the upper surface of said first named boss, a lever, flexible connections between said lever and the dampers of the furnace, connections between said cap and said lever for operating the lever through the movement of the cap, said last named connections comprising integral arms secured to said cap, an integral yoke connected with one end of said lever, links connecting the ends of said arms with said yoke, and a support carried by the outer casing, said lever being pivotally connected to said support.

4. In a draft regulator for steam boilers, an outer casing, a top therefor provided with a central boss having an opening therethrough, said boss extending above the outer surface of the top and below the inner surface of the top, the upper and lower faces of the boss being surfaced or ground, a bell-shaped member being disposed within said outer casing and being provided with a central boss at its top having an upper ground face to form a tight fit with the upper face of the first named boss, a rod carried by the boss on said bell-shaped member and arranged to extend through the opening in the first named boss, said rod being smaller than the opening to provide clearance between the rod and the walls of the opening, and a cap carried at the upper end of said rod having a lower surface ground to permit a tight fit against the upper surface of said first named boss.
